UNITED STATES PATENT OFFICE.

DONALD B. WINTER, OF FALL RIVER, MASSACHUSETTS.

HALF LAP.

Application filed May 12, 1924. Serial No. 712,843.

To all whom it may concern:

Be it known that I, DONALD B. WINTER, a citizen of the United States, residing at Fall River, in the county of Bristol and State of Massachusetts, have invented certain new and useful Improvements in Half Laps, of which the following is a specification, reference being had therein to the accompanying drawings.

10 The principal objects of my invention are to obtain the greatest efficiency in operation, durability in structure, simplicity and uniformity in manufacture, accessibility and ease in removal and restoration of parts and 15 savings in cost of manufacture and of repairs. These objects are obtainable and result primarily and broadly speaking,—

First,—through avoiding in the construction of my half-lap, the dissimilarity and 20 inaccuracy in the structure and the parts of the half-lap, due to using as the center of the measurements for said construction, the center of the shaft upon which the half lap revolves, by using as a common center of 25 measurements, the center of the combing-arc which, as is well known, is eccentric to the said center of the shaft; and using arcs struck from said eccentric center, determining the pitch of the slots and their matrices, 30 the depth of the slots, the pitch of the brush surfaces of the comb-stock, and the location of the locking means for the matrices; all of which results in matrices and slots identical as to form, and in new and identical comb- 35 stock brush surfaces, and identity as to the relationship between the brush surfaces and matrices; second, by substituting for individual locking means for each matrix, means for simultaneously and positively seating 40 and locking all of the matrices in operative position in their respective slots in the comb-stock, and simultaneously unlocking the same.

45 The drawings illustrate the principles of the features of my invention, and the best embodiment of the same now known to me. They are reproductions of mechanical drawings of the structure, some of which are twice its normal size, in order that the operative dimensions, and angles, may be substantially learned by measurement, without the necessity of naming them hereinafter.

Fig. 1 is an end view of the half-lap, and its rotary brush;

Fig. 2 is a fragmentary view of the lap 65 and brush, showing the brush engaging the needles and the "brush" surfaces of the half-lap; Figs. 1 and 2 being normal size;

Fig. 3 is a diagram, double size, showing how identity of form and structure of each 60 slot, matrix, "brush" surface, etc. may be attained;

Fig. 4 is an end view of half-lap, with locking device;

Fig. 5 is a plan of same;

Fig. 6 is a section of same on line 6—6 Fig. 4, showing a matrix with needles, and rings to lock the matrix in the comb-stock;

Fig. 7 shows end view of modified form 70 of matrix and locking ring;

Fig. 8 is a plan thereof; while

Fig. 9 is a section of the modification, on line 9—9, Fig. 7, showing the form given 75 to a matrix, for the reception of its locking rings.

A shaft 1, Figs. 1 and 3, has mounted thereon, a central barrel 1^a, upon which is removably secured by screws, a comb-stock 2 whose inner curved surface 3, resting upon the barrel, has as its center 4, that of the 80 shaft; while the center of the longitudinal axis of the comb-stock, required for successful use and in the manufacture of the comb-stock, is slightly eccentric to that of the shaft, and is the center 5 of a "combing"-arc 6, Fig. 3. From this center 5, Fig. 3, are struck arcs designated as a "slot tangency" arc 7; a "depth slot" arc 8; an "outer surface" arc 9; and a "brush surface tangency" arc 10; there being here 90 shown twelve matrices 11. The "combing"-arc 6 is therefore divided into eleven equal spaces, and from each of the resulting twelve points as 12 (which, in fact, are the highest points of the matrices, called the matrix 95 "peaks," and form the bases of the needles of the matrices), a line 13 is drawn tangent to the "slot tangency" arc 7, and represents the forward longitudinal plane of each matrix 11 and its slot. Also from each of these points 12 is drawn a line 14 tangent to the "brush surface tangency" arc 10, said line 100 passing through a predetermined point 15 at the front plane of the next rearward

matrix and slot, said line representing the "brush surface" plane 14, which is made up of the outside plane or brush surface 16 of the matrix, and the outside stock or "brush surface" 17 of the comb-stock, said point 15 being a predetermined distance below the point 12 in the combing arc, from which point 12 the line 14 is drawn to represent the next rearward "brush surface" plane.

10 The depth of each slot is determined by the intersection of the plane 13 of its front face with the "depth slot" arc 8; while the rear face of these slots and of each matrix are determined by a line 18 drawn parallel 15 with the front face 13 at a distance equal to the thickness of a matrix 11 and extending from the brush surface plane 14 to the base 19 of the slot.

As the needles 20 are all of the same 20 length, the position of the rows of needles of different sizes on their respective matrices is determined by the distance which it is necessary for them to project from their matrix for their points to touch the "needle point" arc 21 which is struck from the center 4 of the shaft 1. The front of each matrix 11 is recessed for the reception of the needles 20 to a depth equal to the thickness of the needles, plus the thickness of the solder by 30 means of which they are held to the matrix; the thickness of the needles, solder and matrix being equal to the thickness of the matrix slot.

The device for locking the matrices in 35 their respective slots consists of two curved metallic members 30, Figs. 1, 4, 5 and 6, each rectangular in cross section, having a curvature struck from said combing arc center 5, as by arcs 31 and 32, each end portion of 40 said member being provided with a suitable hole 33 and screw 34. To aid in removal, the comb-stock below each matrix is notched at 35, to admit a tool by means of which the matrix can be pushed upward out of the slot.

45 Before giving a more detailed description of the structure, the operation, and the advantages of, my half-lap, I will state some facts which are essential to all good combing, and which must be clearly understood.

50 Every half-lap is mounted upon its cylinder shaft, see Fig. 1, and is in constant rotation. The fringe of cotton 40 to be combed is held in the path of the needles by a pair of nippers 41. The largest and heaviest 55 needles at the front A of the half-lap, strip the fringe of cotton known as the "beard" first, break it up, and prepare the way for the finer and finer needles toward the back B of the half-lap. The first several rows of 60 needles remove the short fibres which are not long enough to be held by the nippers, and the last rows of fine needles polish the remaining long fibres and lay them in parallelism.

65 On all half-laps, the increasingly fine

needles toward the back B must be given an increasing amount of support. This is done by raising the top or peak of each succeeding matrix an equal degree higher than its predecessor. In this way the peaks of the matrices conform to the "combing"-arc, which as already stated, is eccentric to the center of the shaft on which the half-lap revolves.

70 The short fibres, nibs and dirt which are combed from the cotton, naturally seek the 75 combing base of the needles, which is at the peak of the matrix. Before the needles do their next combing, which will be on the next revolution of the shaft, this material must be removed from the base of the needles. 80 This is done by a rotary brush, as C, Figs. 1 and 2, the circumference of which is traveling in the same direction as the circumference of the comb-stock D, but at a greater 85 rate of speed. The bristles 50 of the brush pass between the needles from the rear, and sweep away the material which has collected in front of the needles at their combing bases. If the material is to be thoroughly 90 swept away, the bristles of the brush must be given an unobstructed path. Accordingly the peak of the matrix must be raised above the surface in front of it, in order that the brush bristles may have a clear path through the projecting length of the needles and beyond. In order to obtain brushing of the greatest efficiency, a definite relationship 95 must exist between the matrix peak and the preceding outer surface; and in order to obtain brushing of the same efficiency throughout the half-lap, this relationship must be alike at each row of needles, and, further, this relationship must be constantly maintained. For example, if a matrix peak is not raised high enough above the preceding 100 outer surface, the path of the bristles in front of the needles is obstructed, and the waste material is not removed properly.

105 Conversely, if a matrix peak is too far above the preceding outer surface, the material, which seeks the lowest level, collects too far below to be reached by the bristles of the brush, and as is often the case, this material forms into a hard layer which gradually rises in front of the needles and becomes too firmly entrenched to be dislodged by the brush. The correct relationship between a matrix peak and the preceding outer surface can only be determined after experiment. Once found, that relationship should be made to exist at each row of needles and then maintained, or "flocking", the term given to the collecting of waste material in front of the needles, will result.

110 In order to show the novelty of various 125 features of my invention and their advantages over the prior state of the art, as known and understood by me, I will endeavor to explain certain old structures and the principles employed by them in their operation,

and to differentiate my new features from them; and in so doing I will classify various old apparatus as "Prior means I", "Prior means II", etc., and my new structures as 5 "Feature I of my invention", etc. These "Prior means" and "Features of my invention" I will now particularly describe.

In taking up said means, it is my purpose first of all to show the advantages resulting 10 from making the outer circumference, or the outer surface of the comb-stock, concentric with the combing arc.

The outer surface of each comb-stock on the market is eccentric to the combing arc. 15 The outer surface is sometimes rounded with matrices attached by means of screws, or it may be slotted with tangent brush surfaces, as in the case of the half lap of my invention. In the following discussion the 20 radius of the outer surface is not specified, and only the advisability as to whether or not the outer surface should be concentric with the combing arc is discussed.

Prior means I.—A comb-stock, the outer 25 surface of which is concentric with the combing arc.

Describe any circle, such as 32, from center 5, Figure 4, to represent an outer comb-stock surface concentric with the combing 30 arc. By inspection of the drawing, it can be seen that the following advantages are obtained:

(1) Each matrix is supported to a point an equal distance from its combing peak 12. 35 (2) As matrices of equal width are used to simplify manufacture and to secure accuracy, these matrices of equal width enter into the comb-stock to an equal depth, and may thus be secured equally by a locking 40 means located in the comb-stock.

(3) In the type of half-lap in which there are no slots, the locking means of each 45 matrix which is on the outer surface instead of beneath it, is raised to a point an equal distance from the combing arc so that matrices of equal width may be used.

By describing a circle from center 4, Fig. 4, to fall near circle 32, to represent an outer surface eccentric to the combing arc, 50 it can be seen by inspection that the above advantages do not result.

Prior means II.—A comb-stock having its outer surfaces concentric with its combing arc (as above), the radius of the outer 55 surface being extended until the outer surface arc 9, Fig. 3, passes through the top rear edge of the matrix.

Extend the radius of arc 32, Fig. 4, until the arc passes through the top rear edge 60 of the matrices, as arc 9, Fig. 3. This results in an outer comb-stock surface located similarly to that of the half lap of my invention. By inspection of Fig. 4, it can be seen that through this element the following 65 advantages are obtained.

(1) The matrices are supported equally (means I) and maximumly (means II).

(2) The correct relationship between brush surfaces and matrix peaks, when established, is maintained. This is a necessary feature, as already explained, and is realized through the rigidity of the structure. 70

(3) The needles are supported against the front walls of the slots, thus preventing 75 their working loose from the solder. This is brought about by the material of the comb-stock being raised to surround the matrices and needles.

(4) There are no openings in front of the 80 needle where waste can collect. This is brought about through the absence of possibility of bends in the matrices firmly embedded in their slots.

Waste is prevented from collecting in 85 front of the needles by the action of the brush. The distance below the matrix peak at which the plane of the comb-stock brush surface intersects the plane of the front face of the matrix has been determined after experimentation and is found to be the point of intersection of these two planes at which "flocking" is prevented. 90

Prior means III.—A matrix requiring no 95 adjustment in the comb-stock. Its width and the depth of its slot are such that when the matrix rests upon the bottom of its slot, it is in its adjusted position, and its peak and the needle points of its needles are 100 given the correct elevation. 105

The following advantages result through adopting this element:

(1) The correct relationship between matrix peaks and preceding brush surfaces is 110 established as far as the constant elevation of the matrix peak is concerned.

(2) Each matrix is at all times supported and protected to the same degree. This is because its elevation of the matrix peak in 115 relation to the outer surface of the comb-stock is fixed and constant.

(3) Time and repair bills are saved because it is not necessary to make an adjustment of the matrix in its slot or of the needles to gain the correct height of the needle points. The matrix peak is made to assume a correct as well as a constant elevation through certain features of structure and manufacture which will appear later. 120

Feature I of my invention.—A half-lap having the planes of its matrix slots of equal depth; matrices, and "brush surfaces" of the matrices, tangent to arcs struck from the combing arc center.

From this feature the following advantages result:

(1) The planes of the matrix brush surfaces intersect the front planes of the following matrix at equal distances below the 125 combing peaks. 130

It can be seen that if the matrix slots and matrices were tangent to an arc described from the center other than the combing arc center—that the planes of the matrix brush surfaces would intersect at distances below the matrix peak which would differ at each matrix.

(2) An arc struck from the combing arc center (such as arc 8, Figs. 3 and 4) may be used as a measurement of the depths of the slots. Accuracy results from this, in that this arc is struck from the same center as the arc to which the matrix peaks must conform—the combing arc.

(3) The matrices are divided equally and similarly by the arc of the locking bar seat.

By inspection of Fig. 4 it can be seen that if the matrices are to be divided similarly by an arc such as 32, the arc to which the slots and matrices are tangent and the arc which divides them must be struck from the combing arc center.

Feature II of my invention.—A comb-stock having tangential plane brush surfaces.

(1) Brush surfaces of this kind, as distinguished from matrix brush surfaces, being part of the material of the comb-stock, are solid and stationary and thus maintain their part in the correct relationship between brush surfaces and following matrix peaks, as already explained.

(2) As the comb-stock brush surface occupies the entire space between matrix slots, it is only necessary that the matrix brush surface extend from the front to the back of the slot. The structure of the matrix is therefore much simplified as its front and rear faces are parallel.

Feature III of my invention.—A half-lap in which the comb-stock brush surfaces lie in the planes of the matrix brush surfaces, and are tangent to an arc struck from the combing-arc center.

Under prior means III, it was shown that the elevation of each matrix peak is made stationary. Under feature I, it was shown that the plane of each matrix brush surface intersects the front plane of the following matrix at an equal distance below the combing peak. Now, as the comb-stock brush surfaces are stationary (feature II) and they lie in planes of the matrix brush surface (feature III), the relationship between matrix peaks and preceding brush surfaces is made constant, and identity as to the relationship of brush surfaces to matrix peaks, is attained throughout the half-lap as previously stated.

As both brush surfaces lie in the same plane, the joining of the two is smoothly made, and there is no crevice where waste can collect.

Feature IV of my invention.—A half-lap

having a locking bar seat and locking bar concentric with the combing arc.

The following advantages result from this feature:

(1) The arc of the locking ring shoulder divides the matrices equally and similarly, as explained under feature I, and consequently matrices exactly alike in structure may be used, greatly simplifying manufacture. (There is necessarily a slight irregularity if the matrices are reversed to receive the needles.)

(2) By the use of the locking bar any number of matrices can be removed and replaced as easily as can one matrix, because there are no individual locking means.

(3) As each matrix has no separate locking means, there need be no space left between the matrices for such devices, and therefore the matrices may be placed closer together if it is found necessary to use more matrices than originally provided for. As is well known, the combing arc cannot be lengthened for the reception of more matrices, because of the timing and mechanism of the comb.

Feature V of my invention.—A half-lap in which one single center of measurement is used in its manufacture. The combing arc, outer surface arc, brush surface tangency arc, and the arc determining the position of the locking bar are all described from the common center, viz, that of the combing arc.

The advantages which are the result of this feature follow:

(1) The position of the combing arc is determined with the greatest degree of accuracy because there is no possibility of variation due to the use of more than one common center of measurement. It is also possible to cause the matrix peaks to conform exactly to this combing arc due to the common origin of measurements. Therefore it is certain that each succeeding matrix peak is lifted a correct amount higher than its predecessor, insuring the regular action of the brush, and that each row of increasingly fine needles is given the correct increase of support, preventing to a great extent the bending and breaking of the needles.

(2) As explained under feature III, identity as to the relationship of brush surfaces to matrix peaks is attained throughout the half-lap. This insures brushing of regular effectiveness, and therefore absence of "flocking" of the cotton and breakage of the needles which means better combing and less repairing.

(3) The manufacture of the half-lap is greatly simplified, due to the possible use of a milling machine. During the complete manufacture of the comb-stock the combing arc center is used as a center of revolution. Therefore, manufacture is made much sim-

pler than if it were necessary to shift the center of the revolution as would be the case if more than one common center of measurement were used.

5 Simplicity in manufacture is also introduced in the making of the matrices, by reason of the fact that they are identical in size and shape; and in the making of the locking means, by substituting a single locking bar for separate locking devices for each individual matrix.

The operation of my invention as a whole will now be described. As the cylinder shaft on which the half-lap is mounted is constantly revolving, it will be seen that each fringe of cotton gripped by the nippers will be subjected to the action of the half-lap. The largest and heaviest needles act first on the fringe of cotton entering into the mass 15 and removing nubs, dirt, and the short fibres not held by the nippers. Then follow the succeeding rows of finer needles, all at the correct angle and extending the correct distance to provide the necessary amount of 20 support and to give the most effective combing.

On its downward path, the face of the half-lap is secured clean of waste material by the rotary brush. Each row of needles 30 is acted upon to the same degree by the brush because the matrix peak conforms to a regular arc. Also the bristles of the brush have a clear path through the needles to their working base and beyond, as each matrix peak is lifted the correct distance above the preceding brush surfaces. Further, as the distance of every matrix peak above the preceding brush surface is equal, this brushing is regular in its effectiveness 40 throughout the half-lap. Also, as there are no open spaces in front of the matrices, there is no opportunity for waste material to become lodged. Consequently, as the half-lap is swept clean of waste material at each 45 contact of the brush, there is no "flocking"; therefore better combing, less breakage, and fewer repairs.

It is frequent that hard lap ends of cotton are run through the comber, or a cleaning 50 brush or stick is accidentally inserted into the path of the needles. Being very delicate, the needles are either bent or broken. However slight the damage, these rows of needles should be replaced at once, for bent and 55 broken needles damage the cotton fabrics and cause "flocking". This may be accomplished by unscrewing the screws 34 in the locking bars 30, and removing the bars 60 from the comb-stock, when any number of matrices may be removed, and replaced as simply as can a single matrix, the reason being that there are no individual locking means. The duplicate matrices, which are 65 stamped with numbers corresponding to numbers near the slots they are to occupy,

are pushed into their slots and are locked into place by replacing the locking-bars and screws, in the ends of the comb-stock.

Because it is not necessary to gauge the height of the needle points, because of the simplicity of the locking features, and because, as a result, my improved half-lap can be repaired at the mill, the cost in repairs is much reduced. The cost of freight is also much less, as there is no need to send 70 away an entire half-lap for the purpose of repairing a few rows of needles, as formerly. Only the matrices with damaged needles are now sent. Further, as it is not necessary to send the half-laps away, it is not necessary to 75 keep an extra supply of half-laps on hand to replace the damaged half-laps.

To repeat by reason of my using the combing-arc center as a center of measurement and construction, as for the outer surface of the comb-stock, as for matrix slots and for brush-surfaces and locking bar seat, there is obtained identity, as to form of matrices, as to form of matrix slots, as to 80 pitch of slots, as to comb-stock "brush" surfaces, and as to their distance below the working base of the needles. In short, my endeavor has been to embrace in a half-lap, in as perfect way as I could, not only one 85 that would fulfil the demands as to good 90 combing, durability and ease of repairing, but also one that could be quickly, easily, and cheaply made upon a milling machine. The application of this idea brings about 95 these most desirable results. 100

A modified form of locking device is shown in Figs. 7, 8 and 9. It consists of a curved metallic member 60, rectangular in cross-section, having a curvature struck from the combing-arc center 5, as by arcs 61, 62, each end portion of said member being circular and provided with a suitable hole and screw 63. A slot of a curvature and depth and form corresponding to that of the lock member, is cut in each end of the comb-stock for the reception of this member. Likewise each end portion of each matrix is cut away for the reception of this locking member. Hence, in the formation 105 of a locking device, the curves having the combing-arc center, facilitate the use of the milling machine in reference to the manufacture of the comb-stock. To aid in the removal of each matrix, the bottom of each slot is slightly notched, as at 35. Each bar 110 has ears 64 to aid in removal of bar from the comb-stock. 120

Should one or more matrices require repairs, they may be removed from the comb-stock by unscrewing the screws 63 in the two lock bars 60, removing the bars from the comb-stock; and then by pushing out the matrix from each slot by the use of a tool inserted into the groove under the matrix. 125 Into its place, is pushed a duplicate matrix 130

with corresponding needles; the matrix at once finding its pitch surface in the slot, where it may be seated and locked by replacing the lock-bar and screws in the ends of 5 the comb-stock.

Because I have described how my invention may be made up on a milling machine with the greatest accuracy and economy as to cost, I do not mean it cannot be so constructed 10 by other mechanical methods; or that it may not be substantially embodied in structures made with less accuracy, by machinery or otherwise, for it can be.

Desiring, therefore, to claim my invention 15 and its features in the broadest manner legally possible, what I claim is:

1. A comb-stock mountable upon a shaft, and having a longitudinal axis eccentric to that of the shaft; a multiplicity of matrix 20 slots therein; a matrix for each of said slots, having a brush-surface tangent to an arc struck from said axis as a centre giving the desired pitch to each of said matrix brush-surfaces.

25 2. A comb-stock mountable upon a shaft, and having a longitudinal axis eccentric to that of the shaft; a multiplicity of matrix slots, the plane of the front face of each slot being tangent to an arc struck from said 30 axis as a center; and the depth of each slot being determined by a depth slot arc struck concentrically from said center; a matrix for each of said slots, having a brush surface tangent to an arc struck from said center giving the desired pitch to each of said matrix brush surfaces.

35 3. A comb-stock mountable upon a shaft, and having a multiplicity of longitudinal slots therein; a comb-stock brush-surface in front of each of said slots, whose plane is tangent to an arc struck from a center in a line passing through the center of the shaft.

40 4. A comb-stock mountable upon a shaft, and having a longitudinal axis eccentric to that of the shaft; a multiplicity of longitudinal matrix slots therein; a comb-stock brush-surface in front of each of said slots, whose plane is tangent to an arc struck from said axis as a centre.

45 5. A comb-stock, mountable upon a shaft, and having a longitudinal axis concentric with the combing arc, eccentric to that of the shaft; a multiplicity of longitudinal matrix slots, with opposite parallel plane surfaces, and corresponding outside longitudinal brush surfaces, one in front of each of said slots, the plane of the front surface of each slot, and the plane of the brush surface in front of each slot, being tangent to its respective curved surface, having said eccentric longitudinal axis as a center, the radius for each of said concentric surfaces being determined by the pitch to be given to the brush surfaces and by the pitch to be given 50 to said front surfaces of the slots; and the

depth of each of said slots being identical and predetermined by a curved surface having said eccentric longitudinal axis as a center, the said concentric curved surfaces determining the pitch and the depth of the 55 slots, and the pitch of the brush surfaces.

6. A comb-stock mountable upon a shaft; a multiplicity of longitudinal matrix slots therein; a comb-stock brush-surface in front of each of said slots, whose plane is tangent to an arc struck from a center in a line passing through the center of the shaft; a matrix for each of said slots, whose brush-surface lies in the plane of the following comb-stock brush-surface.

7. A comb-stock mountable upon a shaft, and having a longitudinal axis eccentric to that of the shaft; a multiplicity of longitudinal matrix slots therein; a comb-stock brush-surface in front of each of said slots, whose plane is tangent to an arc struck from said axis as a centre; a matrix for each of said slots having its brush-surface in the plane of the following comb-stock brush-surface.

8. A comb-stock mountable upon a shaft, and having a longitudinal axis eccentric to that of the shaft; a multiplicity of longitudinal matrix slots, with opposite parallel plane surfaces, and corresponding outside longitudinal brush surfaces, one in front of each of said slots, the plane of the front surface of each slot, and the plane of the brush surface in front of each slot, being tangent to its respective curved surface having said axis as its center; the pitch given to the front surfaces of the slots, determining the radius of the curved surface to which their planes are tangent; a matrix for each of said slots, whose combing arc has said axis as a center, and whose top brush surface lies in the plane of the brush surface of the comb-stock which in each case intersects the plane of the front face of the following matrix slot, at an equal 100 distance below the combing-arc, the pitch given to the brush surface planes of the comb-stock determining the radius of the curved surface to which they are tangent.

9. A comb-stock mounted upon a shaft, and having a longitudinal axis eccentric to that of the shaft; a series of slots therein for the reception of matrices, the front face of each slot being tangential to an arc struck from said axis as a center; said matrices; a semi-circular locking-bar to engage said comb-stock and each of said matrices, at a point between the top and bottom of each of said matrices, the curvature of said bar having said longitudinal axis of the comb-stock for its centre; and means for removably securing said locking-bar to said comb-stock to hold rigidly each of said matrices in its respective slot.

10. A comb-stock mounted upon a shaft 120

- and having a longitudinal axis eccentric to that of the shaft; a series of slots therein for the reception of matrices, the front face of each slot being tangential to an arc struck from said axis for a centre; said matrices; a semi-circular locking bar to engage said comb-stock and each of said matrices, the end portions of the comb-stock and each of said matrices being cut away 5 to form a semi-circular seat for said locking-bar, the curvature of said bar and said seat having said longitudinal axis of the comb-stock for its centre; and means for removably securing said locking-bar in said seat to hold each of said matrices in operative position in its respective slot in said comb-stock.
11. A comb-stock mountable upon a shaft; and having a longitudinal axis eccentric to that of the shaft; a multiplicity of slots, the front face of each slot being tangential to an arc struck from said axis as a center; the depth of each slot being determined by a depth slot struck concentrically from said center; matrices of equal width resting upon the bottom of each of their respective slots; a locking bar to engage said comb-stock and each of said matrices, the end portions of said comb-stock and each of said matrices being cut away and receiving said locking-bar to engage said comb-stock and each of said matrices; and means for removably securing said locking-bar in locking engagement with said comb-stock and each of said matrices.
12. A comb-stock mountable on a shaft and having a longitudinal axis eccentric to that of the shaft; a multiplicity of slots therein, the front face of each slot being tangential to an arc struck from said axis as a centre; matrices in said slots; a locking-bar to engage said comb-stock and each of said matrices, the end portions of said comb-stock and each of said matrices being cut away and receiving said locking-bar to engage said comb-stock and each of said matrices; and means for removably securing said locking-bar in locking engagement with said comb-stock and each of said matrices.
13. A comb-stock mountable upon a shaft and having a longitudinal axis eccentric to that of the shaft; a series of slots therein for the reception of matrices; said matrices; semi-circular locking-bar to engage said comb-stock and each of said matrices, the end portion of the comb-stock and each of said matrices being cut away to form a semi-circular seat for said locking-bar, the curvature of said bar and said seat having said longitudinal axis of the comb-stock for its center; and means for removably securing said locking-bar in said seat to hold each of said matrices in operative position in its respective slot in said comb-stock.
14. A comb-stock mountable upon a shaft, and having a longitudinal axis eccentric to that of the shaft; a multiplicity of matrix slots, the front face of each slot being tangential to an arc struck from said axis as a center; and the depth of each slot being determined by a depth slot arc struck concentrically from said center; matrices of equal width resting upon the bottoms of their respective slots; a semi-circular locking bar to engage said comb-stock and each of said matrices, the end portion of the comb-stock and each of said matrices being cut away to form a semi-circular seat for said locking bar, the curvature of said bar and said seat being concentric with the slot tangency arc; and means for removably securing said locking bar in said seat to hold each of said matrices in operative position in its respective slot in said comb-stock.
15. A comb-stock, mountable upon a shaft, and having a longitudinal axis, common with that of the combing-arc and eccentric to that of the shaft; a multiplicity of longitudinal matrix slots, with opposite parallel plane surfaces, and corresponding outside longitudinal brush surfaces, one in front of each of said slots, the plane of the front surface of each slot, and the plane of the brush surface in front of each slot, being tangent to its respective curved surface, having said eccentric longitudinal axis as a center; the radius for each of said concentric surfaces being determined by the pitch to be given to the brush surface and by the pitch to be given to said front surface of the slot, the depth of each and all of said slots being identical and predetermined by a curved surface having said eccentric longitudinal axis as a center; the said concentric curved surfaces determining the pitch and depth of the slots, and the pitch of the brush surfaces; matrices for said slots, said matrices being of equal width and resting on the bottom of said slots; a concentric locking bar to engage said comb-stock, and each of said matrices at points between the top and the bottom of each of said matrices; and means for removably securing said locking bar to said comb-stock to hold rigidly each of said matrices in its said respective slot.
16. A comb-stock mountable upon a shaft and having a longitudinal axis eccentric to that of the shaft; a multiplicity of longitudinal slots therein; a comb-stock brush-surface in front of each of said slots whose plane is tangent to an arc struck from said axis as a centre; a matrix for each of said slots, having its brush-surface in the plane of the following comb-stock brush-surface; suitable locking means to engage said comb-stock and each of said matrices, for removably securing in one operation all of said matrices in their respective slots.
17. A comb-stock mountable upon a shaft

- and having a longitudinal axis eccentric to that of the shaft; a multiplicity of longitudinal slots therein; a comb-stock brush-surface in front of each of said slots whose 5 plane is tangent to an arc struck from said axis as a centre; a matrix for each of said slots, having its brush-surface in the plane of the following comb-stock brush-surface; a locking-bar to engage said comb-stock and each of said matrices at points between the 10 top and bottom of each of said matrices; and means for removably securing said bar to said comb-stock to hold rigidly each of said matrices in its respective slot.
15. 18. A comb-stock mountable upon a shaft and having a longitudinal axis eccentric to that of the shaft; a series of slots therein for the reception of matrices, the front face of each slot being tangent to an arc struck from said axis as a centre; a comb-stock brush-surface in front of each of said slots, whose plane is tangent to an arc struck from said axis as a centre; a matrix for each of said slots, having its brush-surface lying in the plane of the following comb-stock brush-surface; a locking-bar concentric with said 20 arc to engage said comb-stock and each of said matrices at points between the top and bottom of each of said matrices; and means for removably securing said bar to said comb-stock to hold rigidly each of said 25 matrices in its said respective slot.
25. 19. A comb-stock mountable upon a shaft and having a longitudinal axis eccentric to that of the shaft; a multiplicity of longitudinal slots therein; a comb-stock brush-surface in front of each of said slots whose plane is tangent to an arc struck from said axis as a centre; a matrix for each of said 30 slots having its brush-surface in the plane of the following comb-stock brush-surface; a locking-bar to engage said comb-stock and each of said matrices, the end portions of 35 said comb-stock and each of said matrices

being cut away and receiving said locking-bar to engage said comb-stock and each of said matrices; and means for removably securing said locking-bar in engagement with said comb-stock and each of said matrices.

45. 20. A comb-stock mountable upon a shaft and having a longitudinal axis eccentric to that of the shaft; a multiplicity of longitudinal slots therein; a comb-stock brush-surface in front of each of said slots whose 50 plane is tangent to an arc struck from said axis as a centre; a matrix for each of said slots having its top or brush surface in the plane of the following comb-stock brush-surface; a locking-bar concentric with said 55 arc to engage said comb-stock and each of said matrices at points between the top and bottom of each of said matrices; and means for removably securing said bar to said comb-stock to hold rigidly each of said 60 matrices in its said respective slot.

65. 21. A comb-stock mountable upon a shaft and having a longitudinal axis eccentric to that of the shaft; a series of slots therein for the reception of matrices, the front face of 70 each slot being tangent to an arc struck from said axis as a centre; a comb-stock brush-surface in front of each of said slots, whose plane is tangent to an arc struck from said axis as a centre; a matrix for each of said 75 slots, having a brush-surface lying in the plane of the following comb-stock brush-surface; a locking-bar to engage said comb-stock and each of said matrices at points between the top and bottom of each of said 80 matrices; and means for removably securing said bar to said comb-stock to hold rigidly each of said matrices in its respective slot.

85. In testimony whereof I hereunto affix my signature.

DONALD B. WINTER.
